TRAPPED DUST TRANSFER DEVICE

Robert D. Poet, Altoona, Pa.

Application August 28, 1931. Serial No. 560,000

5 Claims. (Cl. 220—86)

This invention relates to a device adapted to be used to advantage for transferring dust from a sweeper bag into a receptacle and consists in the novel features hereinafter described and 5 claimed.

An object of the invention is to provide means such as indicated which may be effectively used for transferring the dust and at the same time preventing any of the dust from escaping. With 10 this object in view, the device includes a container for the receptacle to which the dust is transferred being provided with a cover for the container, said cover having an opening. A collar is provided with slidably overlapping end portions and 15 one end of the collar is fixed to the cover at the opening thereof. Blades are attached to the collar and have end portions slidably under the top of the cover. The collar is adapted to enter the mouth of the sweeper bag and means are provided 20 for dilating the collar whereby it fits snugly in the mouth of the sweeper bag and the dust cannot escape as it is being transferred from the sweeper bag into the receptacle.

In the accompanying drawings:

25 Figure 1 is a vertical sectional view of the device.

Figure 2 is a horizontal sectional view cut on the line 2—2 of Figure 1.

Figure 3 is a similar view cut on the line 3—3 30 of Figure 2.

Figure 4 is a detailed transverse sectional view cut on the line 4—4 of Figure 3.

Figure 5 is a perspective view of one of the blades used in the device.

35 Figure 6 is a detail sectional view, looking downward, and taken through the overlapping walls of the collar strip just above the plane of the up-standing flanges of the overlapping blades.

As illustrated in the accompanying drawings, 40 the sweeper bag is indicated at 1 and the receptacle bag into which the dust is to be deposited is indicated at 2. The apparatus consists of a container 3 adapted to receive the bag 2, the said container being provided with a bail handle 4.

45 A cover 5 is adapted to close the upper end of the container and the cover is provided with lugs 6 adapted to enter the eyes 7 of links 8 which are connected by means of springs 9 with staples 10 attached to the container 3. By this means 50 the cover is held in position upon the top of the container.

The cover is provided with a central opening 11. A collar strip 12 is located in said opening and bent in general circular form and having 55 overlapping ends. One end of the collar strip

is fixed to the cover 5 at the edge of the opening 11 thereof. One end of the collar strip 12 is provided at its inner side with a guide 13 which slidably receives a tongue 14 provided at the other end of the collar strip. One end of the collar strip 12 is provided with a slot 15 and finger lugs 16 are mounted upon the said end of the collar strip at the ends of the slot. A bolt 17 is carried by the other end of the collar strip and the said bolt passes through the slot 15 and carries a knob 60 18 over its outer end. A spring 19 is housed in the knob and bears at one end against the end thereof and at its other end against the nut 20 mounted on the bolt 17. The spring 19 is under tension with a tendency to hold the end portions 65 of the collar strip 12 in frictional contact with each other and also to make a tight contact in order that dust may not escape between the overlapping end portions of the collar strip. By placing the edge of the forefinger against one of 70 the lugs 16 and the thumb upon the knob 18 and by closing the thumb toward the finger the knob is moved whereby the collar strip 12 is contracted or dilated as desired.

Blades 21 are provided with upstanding 80 flanges 22. The flanges 22 are attached to the inner surface of the collar strip 12 and the blades 21 extend under the top of the cover 5. The edge portions of the adjacent blades overlap each other as best shown in Figure 2 of the drawings. 85 A spacing ring 23 is attached to the peripheral portion at the top of the cover 5 and at the under side thereof and a plate 24 is attached to said spacing ring and is provided with an edge portion which extends under the overlapping 90 blades 21 and serves as a guide and closure for the end portions of the blades. In use, the mouth of the bag 1 is placed around the collar strip 12 and by using the thumb and forefinger upon the knob and one of the lugs 16 as hereinbefore described, the collar strip 12 is dilated or expanded whereby it fits snugly in the mouth of the bag 1. The bag 1 is then brought to a vertical position and the contents thereof pass down through the collar strip 12 and deposit in the bag 2. Inasmuch as the parts fit snugly against each 95 other, there are no apertures through which the dust may escape into the atmospheric air as it is being transferred from the bag 1 to the bag 2.

As the collar strip is expanded or contracted, the overlapping portions of the blades 21 may slide with relation to each other and thus the blades will close the opening at all times and prevent the escapement of dust.

- Having described the invention what is claimed is:
1. A device for transferring dust from a sweeper bag into a receptacle comprising a container for the receptacle, a cover for the container, said cover having an opening, a collar having slidable overlapping end portions, one of said end portions being fixed to the cover at the opening thereof, blades attached to the collar and having end portions slidable under the top of the cover, said collar adapted to enter the mouth of the sweeper bag, and means for dilating the collar. 80
  5. A device for transferring dust from a sweeper bag into a receptacle comprising a container for the receptacle, a cover for the container, said cover having an opening, a collar having slidable overlapping end portions, spring means for holding the overlapped end portions of the collar in contact, one of said end portions being fixed to the cover at the opening thereof, blades attached to the collar and having end portions slidable under the top of the cover, said collar adapted to enter the mouth of the sweeper bag, and means for dilating the collar. 85
  10. A device for transferring dust from a sweeper bag into a receptacle, comprising a container for the receptacle, a cover for the container, said cover having an opening, a collar having slidable overlapping end portions, one of said end portions being fixed to the cover at the opening thereof, blades attached to the collar and having end portions slidable under the top of the cover, said collar adapted to enter the mouth of the sweeper bag, and means for dilating the collar. 90
  15. A device for transferring dust from a sweeper bag into a receptacle, comprising a container for the receptacle, a cover for the container, said cover having an opening, a collar having slidable overlapping end portions, one of said end portions being fixed to the cover at the opening thereof, blades attached to the collar and having end portions slidable under the top of the cover, said collar adapted to enter the mouth of the sweeper bag, and means for dilating the collar. 95
  20. A device for transferring dust from a sweeper bag into a receptacle, comprising a container for the receptacle, a cover for the container, said cover having an opening, a collar having slidable overlapping end portions, one of said end portions being fixed to the cover at the opening thereof, blades attached to the collar and having end portions slidable under the top of the cover, said collar adapted to enter the mouth of the sweeper bag, and means for dilating the collar. 100
  25. A device for transferring dust from a sweeper bag into a receptacle, comprising a container for the receptacle, a cover for the container, said cover having an opening, a collar having slidable overlapping end portions, one of said end portions being fixed to the cover at the opening thereof, blades attached to the collar and having end portions slidable under the top of the cover, said collar adapted to enter the mouth of the sweeper bag, and means for dilating the collar. 105
  30. A device for transferring dust from a sweeper bag into a receptacle, comprising a container for the receptacle, a cover for the container, said cover having an opening, a collar having slidable overlapping end portions, one of said end portions being fixed to the cover at the opening thereof, blades attached to the collar and having end portions slidable under the top of the cover, 110
